US00D533910S

(12) **United States Design Patent** (10) **Patent No.:** **US D533,910 S**
Dibble et al. (45) **Date of Patent:** **** Dec. 19, 2006**

(54) **EXERCISE DEVICE**

(75) Inventors: **Ryan R. Dibble**, Denver, CO (US);
Patrick A. Warner, Boulder, CO (US);
Eric D. Golesh, Thornton, CO (US);
Brent Christopher, Denver, CO (US);
Edward L. Flick, Denver, CO (US)

(73) Assignee: **Nautilus, Inc.**, Vancouver, WA (US)

(**) Term: **14 Years**

(21) Appl. No.: **29/225,514**

(22) Filed: **Mar. 15, 2005**

(51) **LOC (8) Cl.** **21-02**

(52) **U.S. Cl.** **D21/676**

(58) **Field of Classification Search** D21/673,
D21/674, 676, 675, 662; 482/67, 68, 99,
482/100, 102, 103, 123, 133, 134, 138

See application file for complete search history.

(57) **CLAIM**

We claim the ornamental design of an exercise device, as shown and described.

DESCRIPTION

FIG. 1 is an isometric view of an exercise device showing our new design.

FIG. 2 is a front elevation view of the exercise device of FIG. 1.

FIG. 3 is a right side elevation view of the exercise device of FIG. 1.

FIG. 4 is a rear elevation view of the exercise device of FIG. 1.

FIG. 5 is a left side elevation view of the exercise device of FIG. 1.

FIG. 6 is a top plan view of the exercise device of FIG. 1; and,

FIG. 7 is an isometric view of the exercise device wherein the seat and the armatures are shown in alternate positions. The broken lines are for illustrative purposes only and form no part of the claimed design.

1 Claim, 7 Drawing Sheets
